ELECTRIC CUT-OUT

Ralph S. Bennett, Pittsfield, Mass., assignor to
 General Electric Company, a corporation of
 New York

Application July 14, 1937, Serial No. 153,529

36 Claims. (Cl. 200—126)

The present invention relates to electric cut-outs and has for one of its objects the provision of improvements in fuse cutouts particularly of the automatic circuit reclosing type.

5 Another object of the invention is the provision of a circuit reclosing fuse unit of improved construction and arrangement of parts for use in an electric cutout.

10 A further object of the invention is the provision of improved circuit reclosing mechanism and time delay mechanism for use therewith.

15 As to certain features of the present invention, a still further object is the provision of improved mechanism for carrying out the invention of the copending application of G. F. Lincks, Serial No. 153,508, which application was filed concurrently with the present application and is assigned to the assignee of the present invention.

20 Other objects and details of that which I believe to be novel and my invention will become apparent from the following description and the claims appended thereto, taken in conjunction with the accompanying drawings. While my invention may be incorporated in cutouts of either 25 the open type or the enclosed type as will become apparent hereinafter, I have chosen, as the best means of conveying a complete understanding of all features of the invention, to illustrate and describe three exemplary embodiments thereof 30 as incorporated in enclosed fuse cutouts of the drop-out type.

25 In the drawings, Fig. 1 shows parts of one of the exemplary fuse cutouts in normal operative position; Fig. 2 shows the relative positions of the parts of the cutout after operation of one of the fuses therein; Fig. 3 shows in part the positions occupied by the fuses and other parts of the cutout after drop-out following operation of the final one of the fuses; Fig. 4 is a detail exploded view of the fuse holder supporting parts, 35 circuit reclosing mechanism, and timing mechanism; Fig. 5 shows a second form of cutout embodying the present invention and with the parts in normal operative position; Fig. 6 shows the relative positions of the parts of the cutout of 40 Fig. 5 after operation of one of the fuses therein; Fig. 7 shows in part the positions occupied by the fuses after drop-out following operation of the final one of the fuses; Fig. 8 is a detail view of 45 certain of the parts of the cutout of Fig. 5; Fig. 9 is a detail exploded view of the fuse holder supporting parts, circuit reclosing mechanism, and timing mechanism of the cutout of Fig. 5; Fig. 10 shows a third form of fuse cutout embodying the present invention and with the parts 50

in normal operative positions; Fig. 11 shows the relative positions of the parts of the cutout of Fig. 10 after operation of one of the fuses therein; Fig. 12 shows in part the positions occupied by the fuses and other parts of the cutout of Fig. 10 following operation of the final one of the fuses; and Fig. 13 is a detail exploded view of the fuse holder supporting parts and circuit reclosing mechanism of the cut out of Fig. 10.

5 Referring to the drawings, 10 indicates an electric cutout casing of the type commonly employed in non-reclosing fuse cutout installations. The casing is constructed of porcelain or other suitable insulating material and has an integral- 10 ly formed electric creepage and gas barrier 11 disposed between stationary line terminal contacts 12 and 13 carried by the casing. To the rear of the casing is secured a mounting bar 14 for the attachment of the casing to an electric line pole and cross-arm structure or the like. A hinge 15 bracket 15 is secured to the inner face of the rear wall of the casing adjacent the bottom there- 15 of and is provided with a stop 16 for engaging a fuse holder tube or its hinged supporting element when the fuse holder is in dropped-out 20 position. Contacts 12 and 13 are adapted to have line conductors or leads fastened thereto by means of clamping screws 12' and 13' respectively, and upper contact 12 has a contact finger 17 backed up by means of a spring strip 18, which 25 serves to press the finger 17 downwardly, and has also a pair of spaced resilient contact fingers 19, one of which is shown in the drawings, which 30 are arranged to receive a fuse holder terminal cap therebetween.

35 In the exemplary embodiments illustrated, there are provided a pair of fuse holders 20 and 21 of the expulsion type which consist of fuse tubes of insulating material having contact caps 22 and 23 respectively secured to the upper ends thereof and which have fuse links disposed therein with the upper ends of the fuse links connected respectively to the caps 22 and 23 and the lower ends of the fuse links extending out of the bottoms of the fuse tubes as indicated at 24 40 and 25 respectively. Although in the exemplary embodiment illustrated, only two fuse holders are employed, it will become apparent from the ensuing description that the present invention may be carried out with more than two fuse holders, 45 if desired.

50 Fuse holders 20 and 21 are held rigidly in parallel side by side relationship by means of a fuse holder supporting element 26 of insulation material which has holes or sockets for receiving 55

the fuse holders, as best shown in the detail view of Fig. 4. The fuse holders are held tightly in the supporting element by means of pins 27 and 28 which pass through the supporting element into engagement with the fuse holders and which project outwardly on opposite sides of the supporting element, as indicated in the drawings. Thus the holders are maintained against lateral as well as longitudinal displacement relative to each other. The two fuse holders and their supporting element constitute part of a unitary fuse assembly which is removably supported in casing 10 by means of a lever element 30, one end of which is attached to fuse holder supporting element 26 and the other end of which has a hook-shaped portion 31 for detachable engagement with the hinge pin 32 carried by the hinge bracket 15.

The details of the construction of lever element 30 are best shown in Fig. 4, from which it will be seen that the upper end of the lever has a cross-web 33 from which extend upwardly in rigidly spaced apart relationship two arms 34. The arms 34 are provided with openings, roughly triangular in shape, for receiving pins 27 and also pins 35 carried by fuse holder supporting element 26. Viewing the lever element in its normal position illustrated in Fig. 1, the inner edges 36 of the triangular shaped openings are slightly curved inwardly toward the interior of the triangle, while the outer edges 37 of the openings are substantially straight. The lower edges of the triangular openings are divided into two portions, the inner one of which, designated 40, curves outwardly and upwardly, as viewed when the lever element is in the position illustrated in Fig. 1, to humps 41 substantially midway of the bottom edges, while the outer portions of the bottom edges, designated 42, curve outwardly and downwardly from the humps 41. Lever element 30 is arranged to be latched normally in rigid relation to fuse holder 20 by means of the fuse link extension 24 which is anchored to the lever by means of a suitable terminal clamping device indicated at 43 and which extension is passed around a projection 44 on the lever, as shown in Fig. 1. With the lever held in rigid relation to fuse holder 20 by means of fuse link extension 24, pins 27 on fuse holder supporting element 26 bear against the inner edges 36 of the triangular openings in the lever element while pins 35 rest in the inner corners of the triangular openings formed by the inner edges 36 of the openings and the inner portions 40 of the bottom edges of the openings. When the hinge lever 30 is attached to hinge bracket 15 and is held in rigid relation to fuse holder 20, the unitary fuse assembly may be swung upwardly to its normal operative position illustrated in Fig. 1, wherein contact finger 17 presses downwardly on contact cap 22 of fuse holder 20, while contact fingers 19 engage contact cap 22 to hold the assembly in normal operative position. Thus, the upper end of the fuse link in fuse holder 20 is connected to stationary contact 12 through contact cap 22 and contact fingers 17 and 19. The lower end of the fuse link in fuse holder 20, or extension 24, is connected with lower stationary contact 13 through fuse terminal clamp 43, hinge lever 30 and a contact arm 46 which is pivotally mounted on a pin 47 supported in openings 47' in the arms 34 of the hinge lever. Contact arm 46 is biased into engagement with contact 13 by means of a coil spring 48 and a flexible metal shunt strip 49

extends from hinge lever 30 to the pivotally mounted contact arm to provide a path of good electrical conductivity.

The fuse holder supporting arrangement described in the preceding paragraph is such that upon operation of the fuse link in fuse holder 20, fuse link extension 24 is released to permit movement of the fuse holder assembly relative to hinge lever 30. The outward force due to the pressure of spring biased arm 46 against contact 13 tends to cause the lower end of the assembly to swing outwardly, while the upper end of the assembly is latched in its inward position by the contact fingers 19. The outward movement of the lower end of the assembly is limited to a substantially pure pivoting of the lower end of the assembly about the upper end of the assembly by the formation of the edges of the triangular openings in the hinge lever. This is due to the fact that during the initial outward swinging of the hinge lever about hinge pin 32, pins 27 ride upwardly along the inner edges 36 of the triangular shaped openings, while the pins 35 ride upwardly along the inner portions 40 of the bottom edges of the triangular openings so that pins 35, up to the time that they reach the humps 41, do not follow arcs having hinge pin 32 as their center, but rather follow paths which are substantially arcs of circles having a point adjacent the upper end of fuse holder 20 as their center. As a result of this arrangement, there is no tendency for contact cap 22 to become disengaged from contact fingers 19 during the initial outward swinging of the lower end of the fuse holder assembly.

The supporting hinge mechanism just described is a modification of that disclosed and broadly claimed in U. S. Letters Patent No. 2,081,814 to Benjamin R. Hermann, which latter hinge mechanism also may be employed in the practice of the present invention. It is contemplated also that other suitable forms of supporting mechanism such as, for example, that disclosed and claimed in U. S. Letters Patent No. 2,081,826 to George F. Lincks, may be employed in the practice of the present invention as set forth in connection with the first embodiment now being described or the other two embodiments described hereinafter.

The initial outward swinging of the lower end of the fuse holder assembly is stopped and the fuse holder assembly is maintained in a second position, illustrated in Fig. 2, by the wedging action furnished by engagement of pins 35 with humps 41 and the engagement of pins 50, rigidly mounted on hinge lever 30, with a detent arm 51 of insulation material. This detent arm 51 is rigidly mounted on and extends inwardly from a U-shaped member 52 which is pivotally mounted on pins 28 and depends from fuse holder supporting element 26. The U-shaped element 52 is normally held in rigid relation to fuse holder 20 by means of fuse link extension 25 which is anchored to a fuse terminal 53, carried by the lower end of the U-shaped member 52, by means of a suitable terminal clamping device such as indicated at 54. With the fuse holder assembly in its second position illustrated in Fig. 2, the cutout casing door 55, attached to the fuse holders, is in a partially open position to give indication of operation of the fuse link in fuse holder 20.

Door 55 is pivotally attached to the fuse holder supporting element or clamp 26 by means of a bracket 56 carried by the door and having open-

ings 57 formed for snap engagement with pins 28 carried by the fuse holder supporting element. Thus the door and the fuse holders are rotatable relative to each other about pins 28. Provision for relative movement apart of the fuse holders and door is necessitated by the special construction of the door which has a recess 60 in the inner face thereof for accommodating the outer fuse holder 21, a portion of the fuse holder supporting element 26 and other parts of the mechanism herein described. Cutout casings as ordinarily employed in non-reclosing fuse cutout installation are relatively shallow since it is necessary for them to accommodate only a single fuse holder. Such casings would have insufficient depth to accommodate a plural fuse holder assembly of the type illustrated. Hence, in order to carry out one of the principal objectives of the present invention, which is the provision of a circuit reclosing fuse unit which may be employed to convert a non-reclosing fuse cutout to a reclosing fuse cutout without modification of the cutout supporting structure, it is highly desirable to provide a door of the type illustrated having the inner face thereof recessed for the accommodation of those parts of the fuse unit which would project beyond the open face of a cutout casing of the type ordinarily provided in non-reclosing cutout installations. Thus it is made possible to install a reclosing fuse cutout of the type illustrated in a relatively shallow casing primarily designed for the accommodation only of a non-reclosing fuse unit and to have the door properly close the open side of the casing to prevent exposure of the internal parts to adverse weather conditions.

A quick releasable latch is provided for holding the fuse holders and door in their normal relationship wherein the fuse holder 21 is disposed in recess 60. This latch comprises a metal clamping bar 61 which has openings in the body portion thereof for receiving the upper ends of the fuse holders and a metal strap 62 mounted on the door with the body portion of the strap slightly spaced from the inner surface of the door to form a socket for receiving a bent-over portion 63 of clamping bar 61. The bent-over portion 63 is formed with a boss 64 for snap engagement with an opening 65 in strap 62. Clamping bar 61 is slideable on the fuse holders, but is arranged to be held normally in engagement with contact caps 22 and 23 by means of upturned clip arms 66 formed integral with the clamping bar and a resilient spacing element 67 carried by the bar, which spacing element is arranged between the two contact caps to press them outwardly into firm engagement with the clip arms 66. For release of the latch to permit relative movement between the upper ends of the fuse holders and the upper end of the door, it is necessary only to slide the clamping bar 61 downwardly on the fuse holders so as to disengage the bent-over portion 63 of the bar from the socket provided by strap 62.

In order to secure reclosure of the electric circuit through the fuse link in fuse holder 21 upon operation of the fuse link in fuse holder 20 and outward movement of the door to indicating position, there is provided a circuit reclosing mechanism the parts of which are best shown in the detail exploded view of Fig. 4. This mechanism includes a pair of switch arms 70 pivotally supported on pivot pins 71 which engage openings 72 in the opposite arms 34 of hinge lever 30 so that the switch arms 70 are rotatable

between the arms 34. A connecting strap 73 extends between the switch arms and is arranged to bear against the side of fuse holder 20 to hold the switch arms in their downward or open circuit position, shown in Fig. 1, when hinge lever 5 30 is latched in rigid relation to fuse holder 20 by means of fuse link extension 24. A pair of spiral springs 74, each of which has one end arranged to press against the hinge lever and the other end arranged to engage an opening 75 in 10 one of the switch arms 70, is provided for biasing the switch arms toward circuit closing position upon release of connecting strap 73 due to relative movement between fuse holder 20 and hinge lever 30. When the switch arms 70 are in circuit 15 closing position, as indicated in Fig. 2, they engage projections 76 carried by U-shaped element 52 to complete an electric connection between fuse terminal 53 and lower contact 13. Stop pins 77 are mounted on projections 76 to 20 prevent further rotation of the switch arms 70 out of engagement with the projections 76.

It is desirable to delay reclosure of the electric circuit through the fuse link in fuse holder 21 upon operation of the fuse link in fuse holder 20 25 so as to make it possible for a temporary fault to clear itself or to be permanently cleared by operation of the fuse link in fuse holder 20. To this end, I have provided a time delay mechanism in the form of a mechanical escapement 30 carried by hinge lever 30 and connected for delaying movement of switch arms 70 from their open circuit positions illustrated in Fig. 1 to their circuit closing positions illustrated in Fig. 2. By reference particularly to Fig. 4, it will be seen 35 that the escape wheel 80 of the timing mechanism is mounted on one end of a shaft 81 which is rotatably supported in openings 82 in the hinge lever arms 34. On the opposite end of shaft 81 is mounted a pinion gear 83 which engages a 40 gear 84 mounted on a rectangular shaped stub 85 formed integrally with one of the pivot pins 71 which support switch arms 70. The pawl carrying element 86, which has pawls 87 arranged to engage the teeth of escape wheel 80, is rotatably mounted on a pivot pin 90 which is mounted in an opening 91 in one of the arms 34 of hinge lever 30. Suspended from element 86 is an arm 92 having nuts 93 screwed on the end thereof to serve as adjustable inertia weights to control 45 the oscillation of element 86. 50

Upon operation of the fuse link in fuse holder 20 which is normally connected between stationary contacts 12 and 13, hinge lever 30 is released so that the lower end of the fuse assembly may 55 swing outwardly, in the manner previously described, to the position illustrated in Fig. 2 wherein the door gives indication of operation of the first fuse. Also, as a result of the relative movement between the hinge lever and fuse holder 20, strap 73 is released to permit rotation 60 of switch arms 70 under the influence of springs 74 from their open circuit positions indicated in Fig. 1, to their closed circuit positions indicated in Fig. 2. This rotation is delayed by means of 65 the gears 83 and 84 and the escapement mechanism comprising escape wheel 80 and pawl carrying element 86. When the switch arms 70 finally reach their circuit closing positions wherein they are in engagement with projections 76 on element 52, the circuit between the stationary contacts 12 and 13 extends through contact fingers 77 and 79, contact cap 22, clamping bar 61, contact cap 23, the fuse link in fuse holder 21, fuse link extension 25, fuse terminal 53, element 52, 75

switch arms 70, hinge lever 30, shunt strip 49 and contact arm 46.

In case of continuing or recurring fault current, the fuse link in fuse holder 21 operates to release fuse link extension 25. Thereupon element 52 is released and is swung to the right, as viewed in the drawings, under the influence of a spring 94 which has one end connected to element 52 and the other end connected to an eyelet 95 fastened to the door. This serves to release detent arms 51 from the pins 50 carried by hinge lever 30 so as to permit further pivoting of the hinge lever relative to the fuse holders. The hinge lever thereupon swings outwardly, under the influence of the pressure exerted by contact arm 46, from its position illustrated in Fig. 2, and pins 35 carried by fuse holder supporting element 26 ride over the humps 41 on to the downwardly extending portions 42 of the lower edges of the openings in the hinge lever arms 34. This permits the fuse assembly to drop downwardly sufficiently to disengage contact cap 22 from latching contact fingers 19 so that the fuse assembly may swing outwardly toward dropped-out position wherein both of the fuse holders are disconnected from the stationary contacts. The positions of the parts of the circuit reclosing mechanism relative to each other and to the door and fuse holders after operation of the fuse link in fuse holder 21 are indicated in Fig. 3 wherein the fuse assembly is illustrated in part in a position intermediate that shown in Fig. 2 and the final dropped-out position. When the fuse assembly is in dropped-out position, the lower end of fuse holder 20 bears against the bottom of hinge lever 30 and the lower edge of the cutout casing to prevent rotation of the fuse holders and door below a substantially horizontal position.

To replace ruptured fuse links the fuse assembly is removed from casing 10 by disengagement of hinge lever 30 from hinge bracket 15. Clamping bar 61 is then disengaged from strap 62 and slid downwardly on the fuse holders so that the fuse holders may be swung outwardly about pins 28 from the recess in the door for removal of contact caps 22 and 23 and insertion of new fuse links in the fuse holders, it being unnecessary to completely detach the fuse holders from the door for this operation. After new fuse links are installed and the contact caps are screwed on the fuse holders, the latter are pressed back into the door recess and clamping bar 61 slid upwardly on the fuse holders and latched in the socket provided by strap 62. Switch arms 70 are then rotated downwardly into parallel relation with fuse holder 20, as illustrated in Fig. 1 and hinge lever 30, latched in rigid relation to fuse holder 20 by drawing fuse link extension 24 taut and anchoring it to the hinge lever by means of clamp 43. Finally the U-shaped element 52 is swung into parallel relation with fuse holder 21, as illustrated in Fig. 1, and latched in place against the action of spring 94 by drawing the fuse link extension 25 taut and anchoring it to terminal 53 by means of clamp 54. The fuse assembly may then be installed in the cutout casing by engaging the hook-shaped portion 31 of lever 30 with hinge pin 32 and rotating the assembly upwardly about hinge pin 32 until contact fingers 19 engage contact cap 22 to hold the assembly in normal operative position. A handle 96 is provided on door 55 for manual rotation of the assembly into or out of normal operative position.

In the embodiment illustrated in Figs. 5 to 8

inclusive, there is provided a fuse holder supporting element 100 having openings or sockets for receiving the fuse holders 20 and 21 in parallel side by side relationship and maintaining them against lateral and longitudinal displacement relative to each other. As best shown in Fig. 9, this fuse holder supporting element has two arms 101 projecting outwardly therefrom in spaced parallel relationship. Adjacent the outer ends of the arms are oppositely disposed openings 102 for receiving a pivot pin 103 and oppositely disposed openings 104 for receiving a pivot pin 105. Pivot pin 103 is arranged to support rotatably between the two arms 101, a contact arm 106 which is biased by means of a spring 107 to engage lower stationary contact 13 carried by cutout casing 10. One end of spring 107 is disposed in a recess 108 in the rear of contact arm 106 while the other end of the spring is mounted on a projection 109 of fuse holder supporting element 100. The opposite ends of pin 105 extend outwardly beyond arms 101 of the fuse holder supporting element and are arranged to support rotatably a hinge lever 110 having two parallel spaced apart arms 111 provided with openings 112 for receiving the ends of pin 105. Hinge lever 110 has a hook-shaped portion 113 for engagement with hinge pin 32 carried by the hinge bracket 15 supported by casing 10. The hinge lever is adapted to be latched in rigid relation to the fuse holder 20 by means of the extension 24 of the fuse link in fuse holder 20, which fuse link extension is passed around the projection 114 of the hinge lever and anchored to the hinge lever by means of a suitable terminal clamp indicated at 115. With the hinge lever latched in rigid relation to fuse holder 20, the fuse assembly may be swung upwardly about hinge pin 32 to its normal operative position, illustrated in Fig. 1 in which it is latched by engagement of contact fingers 19 with contact cap 22 on fuse holder 20. Thus, normally the circuit between the spaced stationary contacts 12 and 13 carried by the casing 10 extends through contact fingers 17 and 19, contact cap 22, the fuse link in fuse holder 20, fuse link extension 24, fuse terminal clamp 115, hinge lever 110 and arms 111, a portion of arms 101 of the fuse holder supporting element 100, and contact arm 106.

A cutout casing door 120 is pivotally attached to fuse holder supporting element 100 by means of a U-shaped bracket 121 which has outwardly projecting ears 122 secured to the door by means of screws 123 and which has spaced apart parallel extending arms 124 arranged to accommodate fuse holder supporting element 100 therebetween, the arms 124 having slots 125 for pivotal and slideable engagement with pins 126 mounted in openings 127 in the opposite sides of the fuse holder supporting element. Door 120 has a recessed inner face for accommodating the fuse holder 21 and the circuit reclosing mechanism to be described hereinafter and has mounted on its inner face a retaining clip 130, the resilient arms of which have openings 131 arranged for quick releasable engagement with projections 132 carried by a clamp 133 mounted on the fuse holders adjacent the upper ends thereof. Clamp 133 is of metal and is mounted in engagement with contact caps 22 and 23 so as electrically to connect these two caps together and thereby provide a connection between the upper end of the fuse link in fuse holder 21, which is connected to cap 23, and contact fingers 17 and 19. The

clamp also aids in maintaining the two fuse holders in proper side by side relationship. Normally, the upper ends of the fuse holders are maintained in their inner positions relative to the door recess by engagement of retaining clip 130 with projections 132 on clamp 133, while the lower ends of the fuse holders are maintained in their inner positions relative to the door recess by means of the extension 25 of the fuse link in fuse holder 21, which fuse link extension is drawn taut and anchored to a fuse terminal 134, carried by a projecting foot 135 formed integrally with the door, by means of a clamp 136. Fuse terminal 134 is normally isolated from lower stationary contact 13 so that the fuse link in fuse holder 21 is not connected between the stationary contacts. A spring 137, one end of which bears against a portion of the door and the other of which bears against a projection 138 on fuse holder supporting element 100, tends to force the door outwardly with respect to the fuse holders to the extent permitted by the length of slots 125, but relative movement apart of the lower ends of the fuse holders and the lower end of the door normally is prevented by fuse link extension 25.

In order to secure reclosure of the circuit through the fuse link in fuse holder 21 upon operation of the fuse link in fuse holder 20 there is provided a circuit reclosing mechanism which 30 includes a movable contact 140 mounted on the lower end of a bellows 141 which is attached to a barrier element 142 supported by the door. On the other side of the barrier 142 from bellows 141 is a second bellows 143 which is accommodated in 35 a cavity formed in the inner face of the door. These two bellows are filled with a fluid, as indicated at 144, and when contact 140 is forced upwardly into its open circuit position illustrated in Fig. 1, the fluid forced through an orifice 145 in barrier 142 creates a pressure in bellows 143 which tends to force fluid backward through the orifice 145 into bellows 141 to expand the latter and move contact 140 into engagement with fuse terminal 134. If desired, bellows 141 may be 40 provided with a compression spring to aid in moving contact 140 downwardly. However, the contact 140 is normally held in its open circuit position by means of levers 146 disposed on opposite sides of fuse holder 21 and rotatably supported on pins 147 carried by depending projections 148 of bracket 121. One end of each of these levers has slotted connection, as indicated at 150, with a pin 151 carried by contact 140, while the other end of each of these levers has a 45 projecting boss 152 arranged to engage an edge of the open side of casing 10, as indicated at 153 in the detail view of Fig. 8. Door 120 has notches 154 for accomodating bosses 152 when the door is in its closed position.

As previously pointed out, the fuse link in fuse holder 20 normally is connected between stationary contacts 12 and 13 carried by the cutout casting and the parts of the circuit reclosing fuse unit are in their positions illustrated in Fig. 5. Upon operation of the fuse link in fuse holder 20, fuse link extension 24 releases hinge lever 110 for movement relative to the fuse holders and contact arm 106 presses against stationary contact 13 under the influence of spring 107 to force the lower end of the fuse assembly outwardly. Arms 111 of lever 110 support therebetween a roller 149 which engages curved surfaces 101 on the underneath sides of the outer ends of arms 101 of fuse holder supporting element 100. The curved surfaces 101 are formed so as to co-

operate with roller 149 during initial outward movement of the lower end of the assembly to limit this initial outward movement to a substantially pure pivoting of the lower end of the assembly about the upper end of fuse holder 20, thereby to insure against disengagement of contact cap 22 from contact fingers 19 during the initial outward movement of the lower end of the assembly. The assembly, after a partial outward movement of the lower end thereof, is stopped in 10 a second position, illustrated in Fig. 6, wherein the door is in a partially open position to indicate operation of the fuse link in fuse holder 20. The restraining of the assembly in the position illustrated in Fig. 6 is accomplished by means 15 of wedging engagement of the ends of a pair of arms 155, rigidly mounted on hinge lever 110, with the free ends of the arms of bracket 121, as shown in Fig. 6. As previously pointed out, bracket 121 is held in its normal position, illustrated in Figs. 5 and 6, relative to the fuse holders by the anchoring of fuse link extension 25 to fuse terminal 134. Also, upon outward movement of the assembly, levers 146 are released to permit the contact 140 to be moved down into engagement with fuse terminal 134 by the expansion of bellows 141 due to the forcing of fluid thereinto from bellows 143. The rate at which the fluid passes through orifice 145 into bellows 141 may be regulated by suitable means such as 30 a set screw 156, thereby providing a timing arrangement for delaying the movement of contact 140 into engagement with terminal 134 so as to provide for clearance of an initial temporary fault before the circuit is reclosed through the fuse link in fuse holder 21. With the parts in the positions illustrated in Fig. 6, the circuit between stationary contacts 10 and 13 extends through contact fingers 17 and 19, terminal cap 22, clamp 133, terminal cap 23, the fuse link in 40 fuse holder 21, fuse link extension 25, fuse terminal 134, contact 140, levers 146, bracket 121, fuse holder supporting element 100, and contact arm 106.

Upon continuing or recurring fault, the fuse 45 link in fuse holder 21 operates to release fuse link extension 25 so that door 120 may be moved outwardly with respect to the fuse holders by means of spring 137. This permits bracket 121 to move outwardly relative to fuse holder supporting element 100 to the extent permitted by 50 the travel of pins 126 in slots 125 and thereby releases the arms 155 for further movement of hinge lever 110 relative to the fuse holders. Contact arm 106 with its biasing spring 107 then becomes operative to force the assembly outwardly and downwardly until contact cap 22 disengages 55 from contact fingers 19, whereupon the fuse assembly swings downwardly to dropped-out position wherein both of the fuse holders are disconnected from the stationary contacts. Fig. 7 illustrates in part the relative positions of the fuse holders, door and circuit reclosing mechanism following release of contact cap 22 from contact fingers 19 but before the assembly reaches final 60 dropped-out position wherein the lower end of fuse holder 20 engages hinge lever 110 and the lower edge of the cutout casing to prevent rotation of the assembly below a substantially horizontal position.

Ruptured fuse links may be replaced in the fuse holders in the same manner as set forth in connection with the first embodiment described, the fuse holders being released at the upper end 70 for outward rotation relative to the door recess 75

by disengaging the arms of retaining clip 130 from projections 132 on clamp 133. Following the installation of new fuse links in the fuse holders and reengagement of the arms of clip 130 with projections 132, hinge lever 110 is latched in rigid relation with fuse holder 20 by passing the fuse link extension 24 around the projection 114 on the hinge lever and then anchoring the fuse link extension to the hinge lever by means 10 of the terminal clamp 115. With the upper ends of the fuse holders latched in their inward positions relative to the door recess by means of retaining clip 130, the lower ends of the fuse holders and their supporting element 100 are pressed in 15 to the door recess and latched in position by drawing fuse link extension 25 taut and anchoring it to fuse terminal 134 by means of clamp 136. The hook-shaped portion of hinge lever 110 is then mounted upon hinge pin 32 and the fuse 20 assembly is rotated into its normal operative position, illustrated in Fig. 1, in which the assembly is latched by engagement of spring contact fingers 19 with terminal cap 22. As the assembly is forced into its operative position in the 25 casing, projections 152 of levers 146 engage the edges of the casing, as shown in Fig. 8, causing the levers to rotate about pins 147 to force contact 140 into its open circuit position illustrated in Fig. 5. Moving the contact 140 upwardly 30 forces fluid from bellows 141 into bellows 143 to create a pressure in the bellows 143, thereby to cock the circuit reclosing mechanism. The door is provided with a handle 157 to be grasped for manually swinging the fuse assembly into or out of normal operative position.

In the embodiment of the invention illustrated in Figs. 10 to 13 inclusive, the fuse holders 20 and 21 are held in parallel side by side relationship, and maintained against lateral and longitudinal displacement relative to each other, by 40 means of a fuse holder supporting element 160 having socket openings for receiving the fuse holders and mounted on the fuse holders adjacent the bottoms thereof, and also by means of clamp 133 mounted on the fuse holders adjacent the upper ends thereof and in contact with terminal caps 22 and 23. A cutout casing door 161 is attached to the fuse holders at the top in a manner similar to that described in connection 45 with the embodiment of Figs. 5-9 by engagement of retaining clip 130 mounted on the door with projecting bosses 132 carried by clamp 133. The lower end of the door is attached to the fuse holders by means of a bracket 162 which has 50 ears 163 secured to the door by means of screws 164 and which has slotted arms 165 disposed on opposite sides of fuse holder supporting element 160 in slidable engagement with pins 166 mounted in openings 167 of the supporting element. As 55 in the previously described embodiments, door 161 has a recessed inner face for the accommodation of fuse holder 21 and parts of the circuit reclosing mechanism, later to be described, which would project beyond the open face of a relatively shallow cutout casing such as ordinarily employed in non-reclosing fuse cutout installations. Door 161 has also a handle 168 to be grasped for manual operation of the fuse assembly into or out of normal operative position.

The fuse assembly is supported in cutout casing 10 by means of a hinge lever 170 which has at one end a hook-shaped portion 171 for detachable hinged connection with hinge pin 32 carried by hinge bracket 15 of the cutout casing and which 60 lever has at its other end a bore 172 through

which passes a pivot pin 173 supported in openings 174 adjacent the outer ends of spaced parallel arms 175 of supporting element 160, so that the lever is pivotally connected to the supporting element and rotatable between arms 175. 5 Hinge lever 170 is arranged to be held normally in rigid relation to fuse holder 20 by means of fuse link extension 24 which is passed around projecting boss 176 on the lower end of the lever and anchored to the lever by means of fuse terminal clamp 177. Rollers 178 are mounted on lever 170 for engagement with curved guide ways 179 on the lower edges of the ends of arms 175 to limit initial outward movement of the fuse assembly to a substantially pure pivoting of the 15 lower end of the assembly about contact cap 22 as and for the purpose set forth in connection with the embodiments previously described. Supporting element 160 has attached thereto also a contact arm 180 which is rotatably mounted on a 20 pin 181 carried in openings 182 adjacent the outer ends of arms 175. This contact arm is biased for engagement with lower stationary contact 13 by means of a coil spring 183, one end of which bears against the back of the contact arm 25 and the other other end of which is supported on the projection 184 and bears against a portion of the supporting element 160. In order to limit the relative movement between the hinge lever and the fuse holder assembly for a purpose to 30 be pointed out hereinafter, there is provided a U-shaped tie wire 185, the connecting portion 186 of which is slidable in a curved slot 187 in the hinge lever and the legs of which U-shaped tie wire have at their ends outturned projections 35 188 which are slidable in slots 189 in the arms 175 of supporting element 160. Normally, when the hinge lever is latched in rigid relation to fuse holder 20, as shown in Fig. 10, the connecting portion 186 of the tie wire is disposed in the lower 40 end of slot 187, while the projections 188 are disposed in the upper ends of slots 189. The lower end of door 161 is normally held in its inward position relative to the fuse holders by fuse link extension 25 which is anchored by means of terminal clamp 190 to a fuse terminal 191 carried by a projection 192 on the inner face of the door. When the door is so held, ledges 193 on the outer ends of the arms of bracket 162 engage projections 45 188 of tie wire 185 to hold these projections 50 in the upper ends of slots 189.

When the parts of the cutout are in the positions illustrated in Fig. 10, the fuse link in fuse holder 20 is connected between stationary contacts 12 and 13, the circuit extending through 55 contact fingers 17 and 19, terminal cap 22, the fuse link in fuse holder 20, fuse link extension 24, fuse clamping terminal 177, hinge lever 170, a portion of the arms 175 of supporting element 160, and contact arm 180. The engagement of rollers 60 178 with guide surfaces 179 aids in providing a path of good conductivity between the hinge lever and the fuse holder supporting element. Upon operation of the fuse link in fuse holder 20, fuse link extension 24 is released to permit relative 65 movement between the fuse holders and hinge lever 170 and the pressure exerted by contact arm 180 against stationary contact 13 due to the action of spring 183 swings the lower end of the fuse assembly to the position illustrated in Fig. 11, 70 the initial outward movement of the assembly being a substantially pure pivoting of the lower end thereof about the upper end thereof as previously set forth. The assembly is restrained in this second position by means of tie wire 185 since

the connecting portion 186 of the tie wire moves into engagement with the upper end of slot 187 in the hinge lever, while the projections 188 of the tie wire are held in the upper ends of slots 189 by the shoulders 193. Under these circumstances, the door is in partially open position to give indication of operation of the fuse link in fuse holder 20, while contact cap 22 is still latched in its connected position by spring contact fingers 19.

A pair of movable contacts 195 are provided for completing an electric connection between lower stationary contact 13 and fuse terminal 191 which is normally isolated from contact 13. These movable contacts 195 are arranged to engage upwardly projecting arms 196 of fuse terminal 191 and are mounted on rods 197 which are slidably supported in openings 198 in a bracket 199 which depends from fuse holder supporting element 160. Flexible leads 200 provide direct electric connection between rods 197 and contact arm 180. Contacts 195 are biased for engagement with fuse terminal arms 196 by means of coil springs 201 but are maintained normally in open circuit position by a detent plate 202 having upwardly extending notched arms 203 arranged to engage notches 204 in contact supporting rods 197. Detent plate 202 is supported by means of a rod 205 which is vertically slidable in a bore 206 in supporting element 160. To the lower end of rod 205 are secured arms 207 which, when the parts of the cutout are in their normal positions illustrated in Fig. 10, are engaged by projections 176 of hinge lever 170 to hold plate 202 in its upper latching position.

Upon release of hinge lever 170 by operation of the fuse link in fuse holder 20, and resulting outward movement of the fuse holders to the position illustrated in Fig. 11, as previously described, hinge lever projections 176 disengage from arms 207 to permit downward movement of rod 205 by means of levers 210 which are arranged to engage a bearing plate 211 on the upper end of the rod. Levers 210 are pivotally mounted on a bracket 212 carried by the door and are normally biased to rotate in a counterclockwise direction, as viewed in the drawings, from their positions illustrated in Fig. 10 to their positions illustrated in Fig. 11 by means of an operating mechanism, indicated at 213, which is connected with the levers by means of a plunger 214. This operating mechanism may be of the fluid bellows type described in detail in connection with the embodiment illustrated in Figs. 5-9 inclusive, or may be of any other suitable type as desired. It is preferably that the operating mechanism include also an adjustable timing means, as pointed out in connection with the embodiment of Figs. 5-9, for delaying the counterclockwise rotation of levers 210.

Upon outward movement of the fuse holder assembly to the position illustrated in Fig. 11 upon operation of the fuse link in fuse holder 20, rod 205 is released for downward movement by lever 210 under the influence of time delayed operating mechanism 213. After a sufficient downward movement of rod 205, the slotted arms 203 of detent plate 202 disengage from the grooves 204 in contact carrying rods 197, whereupon springs 201 force the contacts 195 quickly into engagement with fuse terminal arms 196 to reclose the circuit through the fuse link in fuse holder 221. The reclosed circuit extends from upper stationary contact 12 through contact fingers 17 and 19, contact cap 22, clamp 133, con-

tact cap 23, the fuse link in fuse holder 21, fuse link extension 25, terminal 191, contacts 195, rods 197, leads 200, and contact arm 180 to lower stationary contact 13.

In case of continuing or recurring fault, the fuse link in fuse holder 21 operates to release fuse link extension 25 whereupon springs 201 further expand to swing the lower end of door 161 outwardly about projections 132 and away from the fuse holders. This results in outward movement of bracket 162 so that shoulders 193 release projections 188 of tie wire 185 and the projections slide downwardly in groove 189 to permit further relative movement between the fuse holders and the hinge lever. The assembly then swings outwardly and at the same time drops down sufficiently to disengage contact cap 22 from contact fingers 19 so that the assembly may swing to the dropped-out position whereupon the parts occupy the positions indicated in Fig. 12 and wherein the fuse holders are disconnected from the stationary contacts.

For refusing, hinge lever 170 is disengaged from hinge pin 32 and the fuse assembly is removed from casing 10. By spreading the arms of retaining clip 130 apart, the upper ends of the fuse holders are released for outward movement relative to the door recess so that ready access may be had to contact caps 22 and 23 for removal thereof and for installation of new fuse links in the fuse holders. When the new fuse links are installed and the contact caps replaced on the fuse holders, the upper end of the fuse holder assembly is pressed back into the door recess and latched by means of retaining clip 130 and the lower end of the fuse holder assembly is pressed into the door recess and latched by anchoring fuse link extension 25 to fuse terminal 191, the hinge lever being held against fuse holder 20 to permit shoulders 193 to slide under projections 188 of the tie wire 185. Contacts 195 are then pressed backwardly into their open circuit positions and latched therein by moving the rod 205 upwardly until slotted arms 203 engage notches 204 in rods 197. Upward pressure of rod 205 on levers 210 cocks the operating mechanism 213 for further operation and rod 205 is latched in its upward position by engagement of hinge lever projections 176 with arms 207 on the lower end of the rod. The hinge lever is latched in rigid relation to fuse holder 20 by passing fuse link extension 24 around projection 176 and anchoring the extension to the hinge lever by fuse terminal clamp 177. The assembly is then ready for installation in cutout casing 10 by mounting the hinge lever on the hinge bracket and rotating the assembly around hinge pin 32 until contact arms 19 engage contact cap 22 to hold the assembly in normal operative position with the door closing the open side of the cutout casing.

From the foregoing description, it will be apparent that I have provided circuit reclosing apparatus of improved construction and arrangement of parts which may be furnished to electric operating companies and the like in the form of a single unit embodying a plurality of fuse holders, a circuit reclosing mechanism and time delay mechanism with the necessary connections and means for detachably mounting the unit on a cutout supporting structure of standard design. Such a unit has, among others, the advantages that it may be used as a replacement for similar units or may be made interchangeable with fuse units of the non-reclosing type so that, with- 75

out modification of the cutout supporting structure and stationary contacts carried thereby, an electric cutout of the non-reclosing type may be converted readily to one of the reclosing type, 5 or vice versa, without the necessity for removal of the cutout supporting structure from the line pole or the like upon which the supporting structure is mounted in the field.

It will be apparent also to one skilled in the 10 art that my present invention is not limited to the particular details of the exemplary cutouts illustrated. For example, by simple modifications well within the range of mechanical skill, the illustrated circuit reclosing units may be adapted 15 for use also in cutouts of the open type.

What I claim as new and desire to secure by Letters Patent of the United States, is:

1. A circuit reclosing fuse unit adapted for removable installation in an electric cutout or like casing having spaced contacts mounted therein; 20 said unit comprising in combination a door adapted to close an open side of a cutout or like casing, a plurality of fuse holders, means supporting said holders in substantially parallel side by side relationship on the inner side of said door, said holders being prevented by said supporting means from substantial lateral movement relative to each other, means for connecting a fuse link in one of said holders between spaced contacts in an electric cutout or like casing, means including a movable contact element operable for connecting a fuse link in another of said holders between spaced contacts in an electric cutout or like casing, means for latching said contact element normally in open circuit position, said latching means being releasable in response to operation of a fuse link in said one holder, means operable upon release of said latching means for effecting operation of said contact element to circuit closing position, and timing mechanism connected for delaying the operation of said contact element to circuit closing position.

2. In an electric cutout including a casing and 45 stationary contacts carried thereby, the combination of a door for said casing, a plurality of fuse holders attached to said door, said holders and door constituting part of a unitary fuse assembly, means for movably supporting said assembly in said casing, means for latching said assembly in normally operative position with said door closing an open side of said casing, said latching means being releasable by operation of a fuse link in one of said holders, means for connecting a fuse link in said one of said holders between said contacts, means operable upon release of said latching means for effecting movement of said assembly from normal operative position to a second position, a normally open 55 switch operable for completing an electric connection of a fuse link in another of said holders between said contacts, means releasable by movement of said assembly from normally operative position for effecting closure of said switch and timing mechanism connected for delaying closure of said switch.

3. In an electric cutout, the combination with 70 a casing and spaced contacts supported therein, of means including a movably mounted cover arranged to close an open side of said casing, a fuse holder assembly supported in the casing and including a plurality of fuse holders, means for connecting a fuse link in one of said holders between said contacts, circuit reclosing switching means operable for completing a connection of

5 a fuse link in another of said holders between said contacts, means operable responsively to operation of a fuse link in said one holder for effecting operation of said switching means and movement of said cover to an indicating position, and timing mechanism connected for delaying the operation of said switching means.

4. A circuit reclosing fuse unit adapted for removable installation in an electric cutout or like casing having spaced contacts mounted therein; 10 said unit comprising in combination a door adapted to close an open side of a cutout or like casing, a fuse holder assembly including a plurality of fuse holders supported on the inner side of said door, means for connecting a fuse link 15 in one of said holders between spaced contacts in a cutout or like casing, and time delayed circuit reclosing mechanism operable for completing a connection of a fuse link in another of said holders between spaced contacts in a cutout or 20 like casing, said door having a recess formed in the inner side thereof and arranged to accommodate a substantial portion of said mechanism.

5. A circuit reclosing fuse unit adapted for removable installation in an electric cutout or 25 like casing having spaced contacts mounted therein; said unit comprising in combination a door adapted to close an open side of a cutout or like casing and formed with a recess in the inner side thereof, a fuse holder assembly including a plurality of fuse holders supported on the inner side of said door, means for connecting a fuse link in one of said holders between spaced contacts in a cutout or like casing, circuit reclosing mechanism operable for completing a 30 connection of a fuse link in another of said holders between spaced contacts in a cutout or like casing, and timing mechanism connected for controlling the operation of said circuit reclosing mechanism, at least a substantial portion of 35 said timing mechanism being disposed in said recess in the inner side of the door.

6. An electric circuit reclosing fuse unit adapted for removable installation on a supporting structure having upper and lower stationary contacts; 45 said unit comprising in combination a fuse holder assembly including a plurality of fuse holders and common carrying means therefor, said carrying means supporting said holders in substantially parallel side by side relationship 50 and preventing substantial lateral movement of the holders relative to each other, a hinge member attached to said assembly and adapted for quick detachable hinged mounting of the lower end of the assembly on a supporting structure, 55 means for connecting a fuse link in one of said holders between spaced stationary contacts, circuit reclosing mechanism including a contact element movable relative to said assembly and hinge member for completing a circuit through a fuse link in another of said holders, latching means for restraining said contact element normally in an open circuit position and releasable in response to operation of a fuse link in said one holder, means for effecting operation of said contact element to circuit closing position upon release of said latching means and time delay mechanism for controlling the operation of said contact element.

7. In an electric cutout including a supporting 7 structure and spaced contacts carried thereby, a plurality of fuse holders and common carrying means therefor, a hinge member for hinged mounting of said holders and carrying means on said supporting structure, circuit reclosing mech-

- anism operable responsively to operation of a fuse link in one of said holders for establishing a circuit through a fuse link in another of said holders; said holders, carrying means, hinge member and mechanism constituting part of a unitary assembly for removable mounting on said supporting structure; said mechanism including a contact element supported for movement relative to said holders and hinge member and operable for completing a circuit through a fuse link in said other holder; means including said hinge member for supporting said assembly on said structure removably in an operative position with a fuse link in said one holder connected between said contacts, means releasable in response to operation of a fuse link in said one holder for effecting movement of the assembly to another operative position, and means releasable in response to movement of said assembly from its first mentioned operative position for effecting operation of said contact element to circuit closing position.
8. In an electric cutout, the combination of a supporting structure, spaced stationary contacts carried thereby, a fuse assembly removably mounted on said structure and including a plurality of fuse holders and common carrying means therefor, means for latching said assembly removably in an operative position and arranged to release the assembly upon operation of a fuse link in one of said holders, means for connecting a fuse link in said one holder between said contacts, means operable upon release of the assembly for moving the assembly to another operative position, circuit reclosing mechanism carried by the assembly and releasable by movement of said assembly from its first mentioned operative position for connecting a fuse link in another of said holders between said contacts, and timing means carried by the assembly connected for delaying operation of said circuit reclosing mechanism.
9. In an electric cutout, the combination of spaced stationary contacts, a fuse holder assembly including a plurality of fuse holders and common carrying means therefor, means for supporting said assembly including a hingedly mounted lever pivotally connected with the assembly, means for latching said lever in rigid relation to said assembly and arranged to be released by operation of a fuse link in one of said holders, means for connecting a fuse link in said one of said holders between said contacts, a switching element carried by said lever and movable relative thereto, said switching element being normally held in open circuit position when said lever is latched in rigid relation to said assembly and being operable to a circuit closing position for completing an electric connection of a fuse link in another of said holders between said contacts, and means releasable by relative movement between said lever and said assembly for moving the switching element to circuit closing position.
10. In an electric cutout, the combination of spaced stationary contacts, a fuse holder assembly including a plurality of fuse holders and common carrying means therefor, means for supporting said assembly in operative position including a hingedly mounted lever pivotally connected to the assembly, means for connecting a fuse link in one of said holders between said contacts, means for connecting one end of a fuse link in a second of said holders with one of said contacts, a terminal arranged for connection with the other end of a fuse link in said second holder, a switch element movably mounted on said lever and biased to engage said terminal for connecting the terminal with the other of said contacts, means for latching said lever in rigid relation to said one fuse holder and arranged to release the lever upon operation of a fuse link in said one holder, means operative to latch said switch element out of engagement with said terminal when said lever is latched in rigid relation to said one fuse holder, said switch element latch being releasable by movement of the lever relative to said one holder to permit movement of the switch element into engagement with said terminal, and time delay mechanism carried by said lever connected for delaying the movement of the switch element into engagement with the terminal.
11. In an electric cutout, the combination of spaced stationary contacts, a fuse assembly including a plurality of fuse holders and common carrying means therefor, terminal means at one end of said assembly arranged to connect with one end of a fuse link in each of said holders, means for supporting said assembly removably in an operative position with said terminal means engaging one of said contacts, means for connecting the other end of a fuse link in one of said holders with the other of said contacts, means operable in response to operation of a fuse link in said one holder for connecting the other end of a fuse link in another of said holders to said other contact and for exerting force tending to move the assembly outwardly from its first mentioned operative position to a second operative position, means for latching said one end of the assembly in inward position, and means providing guide ways operatively connected with the assembly for effecting a substantially pure pivoting of the other end of the assembly about said one end of the assembly as the assembly moves from its first mentioned operative position to its second mentioned operative position upon operation of a fuse link in said one holder.
12. A circuit reclosing fuse unit adapted for removable installation on a supporting structure having spaced stationary contacts; said unit comprising in combination a fuse holder assembly including a plurality of fuse holders and common carrying means therefor, means for connecting a fuse link in one of said holders between spaced stationary contacts, a hinge lever pivotally connected with the assembly and adapted for hingedly mounting the assembly on a supporting structure, means provided for latching of said lever in fixed relation to the assembly, said lever being releasable for movement relative to the assembly in response to operation of a fuse link in said one holder, circuit reclosing mechanism including a contact element supported for movement relative to said assembly and hinge lever and operable for completing a circuit through a fuse link in another of said holders, said contact element being normally in an open circuit position, and means releasable in response to movement of said lever relative to said assembly for effecting operation of said contact element to circuit closing position.
13. A circuit reclosing fuse unit adapted to be removably mounted on a supporting structure having spaced stationary contacts, said unit including in combination a fuse holder assembly including a plurality of fuse holders and common carrying means therefor, spaced terminal

- means arranged to engage spaced stationary contacts, means for connecting a fuse link in one of said holders between said terminal means, a lever pivotally connected with the assembly 5 and arranged for hingedly mounting the assembly on a supporting structure, means for latching said lever in rigid relation to the assembly and arranged to release the lever for movement relative to the assembly upon operation of a 10 fuse link in said one holder, a normally open switch movable relative to the assembly to a circuit closing position for completing an electric connection through a fuse link in another of said holders, means releasable by movement of 15 said lever relative to said assembly for effecting operation of said switch to circuit closing position, and time delay mechanism for delaying movement of the switch to circuit closing position.
- 20 14. In a circuit reclosing device, the combination of a fuse assembly including a plurality of fuse holders and common carrying means therefor, means for connecting a fuse link in one of said holders in an electric circuit, means including a movable switch carried by said assembly operable for completing an electric connection through a fuse link in a second one of said holders, a detent carried by said assembly, said switch and said detent being supported for 25 movement relative to each other, latching means for maintaining said switch and said detent normally in locking engagement to hold said switch in open circuit position, said latching means being arranged to be released by operation of a 30 fuse link in said one holder, means operable upon release of said latching means for effecting relative movement between said detent and said switch to release the switch from the detent, and means operable upon release of the switch for 35 effecting movement of the switch to circuit closing position.
15. In a circuit reclosing device, the combination of a fuse assembly including a plurality of fuse holders and common carrying means 40 therefor, means for connecting a fuse link in one of said holders in an electric circuit, means including a movable switch carried by said assembly operable for completing an electric connection through a fuse link in a second one of said 45 holders, a detent carried by said assembly, said switch and said detent being supported for movement relative to each other, latching means for maintaining said switch and said detent normally in locking engagement to hold said switch in open circuit position, said latching means being arranged to be released by operation of a 50 fuse link in said one holder, means operable upon release of said latching means for effecting relative movement between said detent and said switch to release the switch from the detent, time delay mechanism for delaying the release of said switch from said detent, and means operable upon release of the switch for effecting movement of the switch to circuit closing position.
- 60 16. An electric circuit reclosing fuse unit adapted for removable installation on a supporting structure having spaced stationary contacts; said unit comprising in combination a fuse holder assembly including a plurality of fuse 65 holders and common carrying means therefor, means for removable mounting of said unit on a supporting structure, means for connecting a fuse link in one of said holders between spaced stationary contacts, circuit reclosing mechanism 70 including a contact element supported for move- 75
- ment relative to said holders and operable for completing a circuit through a fuse link in another of said holders, a detent, said contact element and detent being supported for relative movement, latching means for maintaining said contact element and detent normally in locking engagement to hold said contact element in open circuit position, said latching means being arranged to be released in response to operation of a fuse link in said one holder, means operable upon release of said latching means for effecting relative movement between said contact element and said detent to release the contact element from the detent, timing mechanism for delaying release of the contact element from the detent, and means operable for effecting movement of the contact element to circuit closing position upon release of the contact element from the detent. 5
17. An electric circuit reclosing fuse unit 20 adapted for removable installation on a supporting structure having spaced stationary contacts; said unit comprising in combination a fuse holder assembly including a plurality of fuse holders and common carrying means therefor, a hinge 25 lever pivotally connected with the assembly and adapted for removable hinged mounting of the assembly on a supporting structure, means for connecting a fuse link in one of said holders between spaced stationary contacts, said hinge 30 lever being arranged to be latched normally in fixed relation to said assembly and to be released for movement relative to the assembly upon operation of a fuse link in said one holder, circuit reclosing mechanism including a contact 35 through a fuse link in another of said holders, a detent arranged to hold said contact element in an open circuit position, said detent and contact element being supported for relative movement, means releasable in response to relative movement between said hinge lever and said assembly for effecting relative movement between said contact element and said detent to release the contact element from the detent, timing 45 mechanism connected for delaying release of the contact element from the detent, and means for effecting movement of the contact element to circuit closing position upon release of said element from said detent. 40
18. In an electric cutout, the combination of a cutout supporting structure, spaced stationary contacts carried thereby, a fuse assembly movably mounted on said supporting structure and including a plurality of fuse holders and common carrying means therefor, means for connecting a fuse link in one of said holders between said contacts, means for connecting a fuse link in a second of said holders between said contacts including a normally open switch, a latch 50 connected with said switch and arranged to engage a portion of said supporting structure for holding the switch in open circuit position, said latch being releasable by outward movement of said assembly relative to said supporting structure, means releasably by operation of a fuse link in said one holder for effecting outward movement of said assembly, and means operable upon release of said latch for effecting movement of said switch to circuit closing position. 55
19. In an electric cutout including a supporting structure and spaced stationary contacts, a circuit reclosing fuse unit removably mounted on said structure and comprising a fuse holder assembly including a plurality of fuse holders 60

and common carrying means therefor, means for connecting a fuse link in one of said holders between said contacts, circuit reclosing mechanism including a contact element movable relative to said holders for completing a circuit through a fuse link in another of said holders, said contact element being normally in open circuit position, and means including a fluid containing collapsible bellows connected with 5 said contact element, releasable in response to operation of a fuse link in said one holder for effecting time delayed movement of said contact element to circuit closing position.

20. An electric circuit reclosing fuse unit 15 adapted for removable installation in an electric cutout or like casing having an open side and spaced contacts mounted therein; said unit including in combination a door adapted to close an open side of a cutout or like casing, a plurality of fuse holders, means supporting said holders on the inner side of said door including a member detachably secured to the inner side 20 of said door and having a plurality of socket openings for receiving said holders in substantially parallel side by side relationship, said member preventing substantial lateral movement of said holders relative to each other, and means including circuit reclosing switching mechanism forming part of said unit operable 25 for effecting successive connection of fuse links in said holders between spaced contacts in a cutout or like casing.

21. In an electric cutout including a casing and spaced stationary contacts carried thereby, 35 the combination of a fuse holder supporting element removably mounted in said casing, a plurality of fuse holders carried by said supporting element and arranged to be connected successively between said contacts, means connecting a fuse link in one of said holders between 40 said contacts, a door for said casing mounted on said supporting element and movable relative to said holders, quick releasable latching means for maintaining said door normally in rigid relation to said holders, and circuit reclosing mechanism supported for removal with 45 said holders and door and operable responsively to operation of a fuse link in said one holder for connecting a fuse link in a second one of said 50 holders between said contacts.

22. In combination, a door adapted to close an open side of an electric cutout casing and having a recess in the inner side thereof, a fuse holder assembly movably attached to the inner 55 side of said door and including a plurality of fuse holders, quick releasable latching means for maintaining said assembly normally fixed with relation to said door with a substantial part of certain of said holders disposed in said recess, and means operative upon release of said latching means to provide for movement of said certain of said holders out of said recess for installation of fuse links therein without detachment of said door from said assembly.

23. In combination, a door adapted to close an open side of an electric cutout or like casing, said door having an elongated recess in the inner side thereof, a fuse holder assembly including a plurality of fuse holders, means attaching said assembly removably to the inner side of the door, and a quick releasable latching means operable 70 for maintaining said assembly substantially fixed relative to the door with a substantial portion of certain of said holders accommodated in said recess, said attaching means, upon release of said

latching means, providing for movement of said certain of said holders out of said recess without detachment of said assembly from the door.

24. In combination, a door adapted to close an open side of an electric cutout casing and having an elongated recess in the inner face thereof, a fuse holder pivotally attached to the inner face of said door, and quick releasable latching means normally operative to maintain said fuse holder fixed with respect to said door with a substantial part of the fuse holder disposed in said recess, said fuse holder upon release of said latching means being swingable out of said recess, without detachment of the fuse holder from the door for ready installation of a fuse link 15 therein.

25. In a fuse device adapted to be mounted in an electric cutout casing, the combination of a cutout casing door, a plurality of fuse holders each having a terminal cap adjacent one end 20 thereof, a metal member having openings for accommodating said holders in side by side relationship and mounted on the fuse holders in engagement with said terminal caps to provide electric connection therebetween, projections on opposite sides of said member, and means for attaching said holders to said door including a pair of arms mounted on said door and arranged to accommodate said member therebetween, said arms being biased into engagement with said 25 member and having openings for receiving said projections.

26. In a fuse device adapted to be mounted in an electric cutout casing, the combination with a plurality of fuse holders and a cutout casing door, of means for attaching said holders to said door including a member having openings for accommodating said holders in side by side relationship and a socket element on said door, said member being slidable longitudinally 40 on said holders and having a portion formed for quick releasable snap engagement with said socket element.

27. In a circuit reclosing fuse unit, the combination of a fuse holder supporting member, a 45 pair of fuse holders supported thereby, a pair of terminal carrying elements attached to said member, a pair of fuse terminals mounted respectively on said elements and electrically insulated from each other, one of said elements being 50 movable relative to one of said holders and being arranged to be held in rigid relation to said one holder by a fuse link in said one holder attached to the fuse terminal carried by said one element, the fuse terminal on the other of said elements 55 being arranged for connection with a fuse link in the other of said holders, and circuit reclosing mechanism including a normally open switch operable responsively to relative movement between said one element and said one fuse holder 60 for establishing an electric connection between said fuse terminals.

28. In a circuit reclosing fuse device adapted for installation in an electric cutout or like casing, the combination of a fuse holder assembly 65 including a plurality of fuse holders and common carrying means therefor, arranged to support the holders in a cutout or like casing for connection of fuse links in the holders between spaced contacts in such casing, a door movably 70 attached to said assembly and arranged to close an open side of a cutout or like casing, a fuse terminal carried by said door and having means for anchoring one end of a fuse link thereto to latch the door in substantially fixed relation

to said assembly, and means operable for effecting successive connection of fuse links in said holders between spaced contacts in a cutout or like casing.

5 29. A circuit reclosing device for installation in an electric cutout or like casing; said device comprising in combination a door for closing an open side of a cutout or like casing, a fuse holder assembly including a plurality of fuse holders 10 and common carrying means therefor, a pivotal connection between said assembly and door adjacent the upper end thereof, a fuse terminal attached to the door adjacent the lower end thereof, means for securing one end of a fuse link in 15 one of said holders to said terminal, thereby to hold said door in substantially fixed relation to said assembly, means for mounting the assembly in an electric cutout or like casing and means operable for effecting successive connection of 20 fuse links in said holders between spaced contacts in a cutout or like casing.

30. In an electric cutout, the combination with a casing having spaced contacts therein, of a 25 fuse holder assembly hingedly supported in said casing and including a plurality of fuse holders, means for releasably restraining said assembly in an operative position with a fuse link in one of 30 said holders connected between said contacts, said restraining means being releasable responsive to operation of a fuse link in said one holder, a door supported for closing an open side of said casing and arranged for movement relative to said assembly, means for latching the door in substantially fixed relation to the assembly and arranged to release the door for movement thereof relative to the assembly in response to operation of a fuse link in another of said 35 holders, means operable responsively to operation of a fuse link in said one holder for effecting movement of said assembly out of said first mentioned operative position and for establishing connection of a fuse link in said other holder between said contacts, and means arranged to restrain said assembly in a second operative 40 position, said last mentioned restraining means being releasable responsively to movement of the door relative to the assembly, to permit movement of the assembly out of said second mentioned operative position.

50 31. In an electric cutout, the combination with a casing having spaced contacts therein, of a 55 fuse holder assembly including a plurality of fuse holders, means for supporting said assembly in said casing including a hingedly mounted lever pivotally connected with the assembly, means for releasably restraining the assembly in an operative position with a fuse link in one of said holders connected between said contacts, said restraining means being releasable responsive to operation of a fuse link in said one holder, a door attached to said assembly for movement relative thereto and arranged to close an open side of said casing, a detent carried by the door, means for latching the door in substantially fixed relation to the assembly and arranged to release the door for movement relative to the assembly in response to operation of a fuse link in another of said holders, means operable responsively to operation of a fuse link 60 in said one holder for effecting movement of the assembly out of said first mentioned operative position and for establishing connection of a fuse link in said other holder between said contacts, and means associated with said lever arranged 65 for cooperation with said detent on the door to

restrain the assembly in a second operative position, said assembly being movable to a disconnected position in response to movement of the door relative to the assembly.

32. In an electric cutout, the combination of a 5 casing, spaced contacts therein, a fuse assembly including a fuse holder and a door for an open side of said casing, said door being connected with said holder for movement relative thereto, means tending to effect movement of the door 10 relative to the holder, means for latching the door in substantially fixed relation to the holder and arranged to release the door for movement relative to the holder in response to operation of a fuse link in the holder, a detent carried by the 15 door, means hingedly supporting said assembly in said casing, means arranged to cooperate with said detent for releasably restraining the holder in an operative position with a fuse link in the holder connected between said contacts when the 20 door is latched in fixed relation to the holder, said restraining means being releasable responsive to movement of the door relative to the holder, and means operable for effecting movement of said holder to dropped-out position upon 25 release of said restraining means.

33. In an electric cutout, the combination of a 30 casing, spaced contacts therein, a fuse assembly including a fuse holder and a door for an open side of said casing, said door being connected with said holder for movement relative thereto, means for latching the door in substantially fixed relation to the holder and arranged to release the door for movement relative to the holder in response to operation of a fuse link in 35 the holder, means for hingedly supporting said assembly in said casing, and means operable for releasably restraining the holder in an operative position with a fuse link therein connected between said contacts when the door is latched 40 in fixed relation to the holder, said restraining means being releasable in response to movement of the door relative to the holder, and the holder being movable to dropped-out position upon release of the restraining means.

45 34. In an electric cutout, the combination of a casing, spaced contacts therein, a fuse assembly including a fuse holder and a door for an open side of said casing, said door being connected with said holder for substantially pivotal movement relative thereto, means tending to effect movement of the door relative to the holder, a fuse terminal on the door, means for securing one end of a fuse link in the holder to said terminal to latch the door in substantially fixed relation to the holder, means for hingedly supporting said assembly in said casing, and means operable, when the door is latched in fixed relation to the holder, for restraining the holder in an operative position with a fuse link in the 55 holder connected between said contacts, said door being releasable by operation of a fuse link in the holder for movement of the door relative to the holder, and said restraining means being releasable by movement of the door relative to the holder for movement of the holder to a dropped-out position.

35. In an electric cutout, the combination of a 60 casing, spaced contacts therein, a movably mounted door arranged normally to close an open side of the casing, a plurality of fuse holders, means supporting said holders in the casing for connection of fuse links therein between said contacts, means for connecting a fuse link in one of said holders between said contacts, means 65

- operable responsively to operation of a fuse link in said one holder for effecting movement of said door from normal position to an indicating position, a contact element operable to a circuit closing position for completing a connection of a fuse link in another of said holders between said contacts, means normally latching said contact element in open circuit position, said latching means being releasable by movement 5 of said door from normal position, and means 10 operable for effecting movement of said contact element to circuit closing position upon release of said latching means.
36. In an electric cutout, the combination of 15 a casing, spaced contacts therein, a movably mounted door arranged normally to close an open side of the casing, a plurality of fuse holders, means supporting said holders in the casing
- for connection of fuse links therein between said contacts, means for connecting a fuse link in one of the holders between between said contacts, means operable responsively to operation of a fuse link in said one holder for effecting movement of said door from normal position to an indicating position, a contact element normally in open circuit position and operable to a circuit closing position for completing an electric connection of a fuse link in another of 10 said holders between said contacts, means releasable by movement of said door from normal position for effecting operation of said contact element to circuit closing position, and timing mechanism connected for controlling the operation of said contact element to circuit closing position.

RALPH S. BENNETT.

CERTIFICATE OF CORRECTION.

Patent No. 2,164,983.

July 4, 1939.

RALPH S. BENNETT.

It is hereby certified that error appears in the printed specification of the above numbered patent requiring correction as follows: Page 3, first column, line 17, for "Hense" read Hence; page 5, first column, line 18, after "other" insert end; page 6, second column, line 26, for "other other" read other; page 7, first column, line 56, for the word "preferably" read preferable; page 9, first column, line 42, claim 8, for "circut" read circuit; page 10, second column, line 66, claim 18, for "releasably" read releasable; page 13, second column, line 3, claim 36, for "between between" read between; and that the said Letters Patent should be read with this correction therein that the same may conform to the record of the case in the Patent Office.

Signed and sealed this 15th day of August, A. D. 1939.
